Primary Examiner — David Muller(74) *Attorney, Agent, or Firm* — Buche & Associates, P.C.; John K. Buche; Bryce A. Johnson(57) **CLAIM**

We claim the ornamental design of a customizable face plate for vise jaws, as shown and described.

DESCRIPTION

FIG. 1 is a front perspective of a customizable face plate for vise jaws.

FIG. 2 is a back perspective of the customizable face plate for vise jaws of FIG. 1.

FIG. 3 is a front view of the customizable face plate for vise jaws of FIG. 1.

FIG. 4 is a back view of the customizable face plate for vise jaws of FIG. 1.

FIG. 5 is a side view of the customizable face plate for vise jaws of FIG. 1, the opposite side view being identical.

FIG. 6 is a cross section of the customizable face plate for vise jaws taken along line 6-6 in FIG. 5; and,

FIG. 7 is a cross section of the customizable face plate for vise jaws taken along line 7-7 in FIG. 4.

In the claims, items shown as broken lines form no part of the claimed design.
